UNITED STATES PATENT OFFICE.

VINCENT FERRARO, OF CHICAGO, ILLINOIS.

GARMENT-POCKET.

1,372,067.

Specification of Letters Patent. Patented Mar. 22, 1921.

Application filed September 7, 1917, Serial No. 190,247. Renewed June 5, 1920. Serial No. 386,920.

To all whom it may concern:

Be it known that I, VINCENT FERRARO, a citizen of the United States, and a resident of the city of Chicago, county of Cook, and 5 State of Illinois, have invented certain new and useful Improvements in Garment-Pockets, of which the following is a specification.

My invention relates to improvements in 10 garment pockets and has for its object the provision of an improved construction of this character, capable of a large variety of uses and simple and efficient in use.

The invention consists in the combinations and arrangements of parts hereinafter described and claimed.

The invention will be best understood by reference to the accompanying drawings forming a part of this specification, and in 20 which,

Figure 1 is an outer side view of a garment pocket embodying my invention.

Fig. 2, a vertical section of the same,

Fig. 3, an outer side view of the pocket 25 shown in a different position of use,

Fig. 4, a vertical section of the arrangement shown in Fig. 3,

Fig. 5, an outer side view showing the pocket in still another arrangement, and 30

Fig. 6, a vertical section of the arrangement shown in Fig. 5.

The preferred form of construction as 35 illustrated in the drawings comprises an ordinary garment 7 such as a coat or the like provided with a substantially horizontal pocket slit 8 therein. A pocket member 9 is provided with an extension 10 at the top of the inner side thereof, said extension being permanently stitched to the inner side of the 40 garment 7 above the slit 8. A cover flap 11 for pocket 9 is also secured to the inner side of the garment 7 above the slit 8 and outside the pocket 9 by means of a line of stitches. A tongue 12 is secured centrally to the inner 45 side of the garment 7 just below the slit 8 and is equipped at its free end with a snap fastener member 13 in the form of the usual snap cup, as indicated. The pocket member 9 is also provided on the inner upper side 50 of the outer side wall thereof with a cooperating snap fastener 14 in the form of a headed stud adapted to fit within the member 13 and engaged therewith as shown in Fig. 6. Hems 15 and 16 are preferably 55 formed on the upper inner side of the outer wall of the pocket member 7 and on the

inner side of the garment 7 below the slit 8, said hems being preferably secured by means of a line of stitches along their lower edges, said line of stitches being extended 60 entirely through the corresponding parts to give an ornamental or finished effect thereto when exposed.

In use the pocket may be arranged on the outer side of the garment, as best shown in 65 Figs. 1 and 2, and used as an ordinary outer pocket having a closing flap. Also, if desired, the closing flap 11 may be inserted within the upper portion of the pocket 9 and the pocket thus used as an ordinary patch 70 pocket without the cover flap, in which position the line of stitches securing the lower edge of hem 15 will be exposed giving an ornamental finished appearance to the pocket. The pocket may also be inserted 75 through the slit 8 as indicated in Fig. 4 and the flap 11 employed on the outer side of the garment or on the inner side, as indicated in Fig. 4. In this arrangement the pocket may be utilized as a concealed or 80 safety pocket and ready access given through the slit 8 to the trouser pockets of the wearer.

When it is desired to utilize the construction as an ordinary inside coat pocket, the 85 flap 11 is shifted to the outer side of the garment and the tongue 12 inserted within the pocket 9 and secured to fastener 14, as shown in Figs. 5 and 6. It will thus be seen that the construction disclosed is capable of 90 use in four or five different arrangements, giving different visual effects to the garment and also different utilities to the pocket.

While I have illustrated and described the preferred form of construction for carrying my invention into effect, this is capable of variation and modification without departing from the spirit of the invention. I, therefore, do not wish to be limited to the precise details of construction set forth, but 100 desire to avail myself of such variations and modifications as come within the scope of the appended claims.

Having described my invention what I claim as new and desire to secure by Letters 105 Patent is:

1. The combination with a garment having a substantially horizontal slit therein, of a pocket member of a width to be readily extended through said slit and having the inner side thereof permanently secured to said garment above said slit; a tongue secured 110

to said garment below said slit and provided at its free end with fastening means; and fastening means on the inner side of the outside portion of said pocket adapted 5 to engage the fastening means on said tongue, substantially as described.

2. The combination with a garment having a substantially horizontal slit therein, of a pocket member of a width to be readily extended through said slit and having the inner side thereof permanently secured to said garment above said slit; a tongue secured to the inner side of said garment below said slit and provided at its free end with a snap fastener member; and a coöperating snap fastener member on the inner side of the outer side portion of said pocket adapted to engage the fastener member on said tongue, substantially as described.

20 3. The combination with a garment having a substantially horizontal slit therein, of a

25 pocket member of a width to be readily extended through said slit and having the inner side thereof permanently secured to said garment above said slit; a tongue secured to the inner side of said garment below said slit and provided at its free end with a snap fastener member; a coöperating snap fastener member on the inner side of the outer side portion of said pocket adapted to engage 30 the fastener member on said tongue; and a cover flap secured to the inner side of said garment, above said slit and outside of said pocket, substantially as described.

35 In testimony whereof I have signed my name to this specification in the presence of two subscribing witnesses.

VINCENT FERRARO.
